UNITED STATES PATENT OFFICE.

LLOYD ESPENSCHIED, OF HOLLIS, NEW YORK, ASSIGNOR TO AMERICAN TELEPHONE AND TELEGRAPH COMPANY, A CORPORATION OF NEW YORK.

REPEATER-CIRCUITS.

1,378,170.

Specification of Letters Patent. Patented May 17, 1921.

Application filed December 19, 1918. Serial No. 267,527.

To all whom it may concern:

Be it known that I, LLOYD ESPENSCHIED, residing at Hollis, Long Island, in the county of Queens and State of New York, have invented certain Improvements in Repeater-Circuits, of which the following is a specification.

This invention relates to composite or other signaling systems carrying two or more signal currents of different character or frequency, and more especially to the amplification of signal currents in such systems. In signaling circuits carrying, for instance, both telephone and telegraph currents, the amplification of the telegraph signals has heretofore been accomplished by mechanical amplifiers in a portion of the circuit not carrying telephone currents. The desirability of amplifying both sets of signals in such a system by a single instrument is obvious, and it is especially advantageous where both use the same metallic circuit in both directions and where the different sets of signal impulses are reduced to the same order of magnitude; but so far as I am aware no such an arrangement has ever been used. In the employment of the thermionic amplifiers, which are by far the most efficient for telephone amplification, it is highly desirable, if not necessary, to interpose a transformer between the amplifier and the line on either side, to separate the high impedance circuits of the amplifier from the lower impedance of the lines and to isolate from the line the batteries associated with the amplifier. The transformers which have been used for this purpose do not however transmit current of the kind used in telegraphy and other signaling systems.

The tendency toward the use of mechanical repeaters in separate circuits metallically connected with the line, for amplifying telegraphic currents, is a natural result of the common habit of looking upon the telegraph current as a direct current. It may however properly be regarded as a wave composed of a number of sinusoidal currents of different frequencies. In this sense the action of the mechanical repeater is one of reforming the telegraph wave. The input side receives an attenuated current building up relatively slowly, while the output side transmits a new wave of greater slope. We may speak of the telegraph sig-

naling waves as encompassing a band of frequencies in the same way that we speak of telephone currents occupying a band of frequencies. The steepness of the telegraph wave is then an indication of the width of the frequency band comprised.

The action of the mechanical amplifier of telegraph currents may be considered as one of receiving currents representing a band of frequencies of which the higher have suffered a disproportionate attenuation by transmission over the line, and of retransmitting a corresponding band of frequencies in which the higher frequencies are supplied in greater proportion than in the received current and in proper phase relations, so that the wave is reformed. The repeating action may be regarded as one of equalizing the current amplitudes by amplifying relatively more the higher frequency components and of readjusting the phase relations. The mechanical relay, however, in its output side generates a square wave which includes currents of frequencies within the telephone range and higher than is essential for good speeds in telegraph signaling. These interfere with the telephone transmission and it is, therefore, necessary in superimposing the relay output upon a telephone circuit to suppress the higher frequencies by means of selective circuits—the well known composite set. Thus the mechanical relay actually equalizes too much, or over equalizes, for use on composited circuits. Considering the mechanical repeater broadly, there may be said to be two steps, one of energy reimbursement, entailing overequalization, and the other one of compensation for the over-equalization, effected by the composite set.

It is one of the main objects of the present invention to overcome these difficulties and defects in the amplification on composite lines and to avoid the inherent limitations of mechanical amplification by employing the thermionic amplifier used for the telephone currents to amplify also the telegraph or other currents in the circuit, combining therewith a composite transformer and attenuation equalizing elements suitable for dealing with all the signal currents. Provision is also made, where necessary, for carrying the D. C. component of the telegraph current around the amplifier.

In the form of the invention described

- below, two transformers are provided functioning over different frequency ranges, one transformer taking up the action at or near the point where the other transformer leaves off. The invention contemplates, however, the use of a greater or less number of transformers where desirable. A single transformer to cover the entire range of frequencies may be used where circumstances 5 make it possible to secure the desired efficiency for all signal currents in this way.
- A further feature of the invention resides in controlling the relative efficiency with which the different frequencies comprising 10 the telephone and telegraph or other transmission ranges are transmitted through the repeater, with the object of compensating for the unequal transmission of these frequencies over the transmission line itself.
- 15 The equalizing action can be introduced by equalizers individual to each of the superimposed channels or by an equalizer common to all channels and capable of equalizing throughout the entire frequency range involved. Equalizing the channels individually requires that additional frequency discriminating circuits be associated with the equalizers in order that they be confined to the particular range of frequencies for which 20 each is intended, just as in the case of input and output transformers operating to transform only in a prescribed range of frequencies. The means for doing this are shown subsequently in connection with the accompanying figures.
- 25 It should here be noted that division of the frequency range between equalizers need not necessarily be coincident with the division of the frequency range between the communication channels. In fact, where discreet equalizers are employed for individual channels, their effects may overlap to form substantially continuous equalization throughout the entire frequency range. This 30 is desirable because it enables the range of frequencies between the telegraph and telephone channels to be usefully employed either by operating the telegraph as a higher speed channel and thereby using a broader frequency band, or by superimposing one or more other signaling channels in the range of frequencies between the telegraph and telephone channels. Such an alternating current channel may be employed either for 35 telegraph signaling or for telephone signaling. In fact it is common in the operation of compositored telephone and telegraph circuits to employ for telephone signaling a channel of 133 cycles which is in the range referred to. It is desirable to repeat this channel likewise in the common amplifier and to adjust the transmission of it over the entire system in a manner similar to the transmission adjustment of the other channels, *i. e.*, by suitable equalization.

The invention will be more fully understood by reference to the accompanying drawings, in which Figure 1 shows diagrammatically one embodiment thereof applied to a one-way repeater, Fig. 2 shows an arrangement for a two-way repeater embodying the invention, Fig. 3 shows a modification and Figs. 4 and 5 show curves illustrating the two methods of equalization.

In Fig. 1 the incoming circuit is indicated at 1-1 and the outgoing circuit at 2-2. The circuit 1 is connected with the primary windings of the transformers 3 and 4, which may be regarded as together constituting a composite input transformer. The windings 40 at 3 and at 4 are on separate core as indicated by the dotted lines and are designed, respectively, for the frequencies represented in the telephone and telegraph currents. The windings of the separate transformers 45 may be either in series or parallel. Where they are in series as shown on the drawing it is preferable, in order to avoid any unbalance in the telephone circuit, to divide the windings of one of them (here shown as the transformer 3) into two equal sections (5 and 6) between which the windings of the other transformer are connected. The attenuation equalizers 7 and 8 for the telephone currents and telegraph currents respectively, are also preferably connected between the halves of the primary windings of their respective transformers for avoiding unbalance in the system. The equalizer for the telephone currents may however, if 50 desired be connected in parallel with its transformer, and no unbalance is produced by this arrangement. These equalizers may assume a variety of forms depending upon circuit conditions and the character of the 55 currents, that shown for the telephone currents consisting of resistance 9 a part, 9' of which is shunted by an inductance 10 and capacity 11. The equalizer shown for the telegraph currents comprises merely a capacity 12 and a resistance 13 in parallel. The transformer itself, especially with the lower frequencies such as the telegraph, may by proper design, be made to coöperate in the equalization. The selective effect of 60 these devices depends upon the values given their various elements and, as is well understood, their effect in général is to increase the attenuation of the lower frequencies to compensate for the greater attenuation of 65 the higher frequencies occurring in the transmitting circuit proper. It may be noted here in passing that the use of such an equalizer is impractical with mechanical repeaters because it weakens the already weak 70 current to a point where it is insufficient to satisfactorily operate a repeater of that type. A condenser 14 is placed in series with the attenuation equalizer 7 for preventing the telegraph currents from passing through it 75.

instead of through the telegraph transformer 4. Telephone currents are prevented from being diverted from their normal path through the telephone equalizer into the telegraph transformer by the leakage inductance of said transformer. This inductance will be sufficiently large in ordinary cases. If, however, it is not, or if the internal capacities between windings are such as to permit the passage of telephone currents, additional inductances sufficiently large to exclude the telephone currents will be added in series with the transformer windings.

The secondary windings of the transformers 3 and 4 are connected in the same relation, here shown as series, as their primaries. When connected in series as shown a condenser 15 is connected in shunt to the secondary winding of transformer 4 for affording the high frequency telephone currents a path around the high inductance of that winding.

The input side of the thermionic amplifier 16 is connected to the output side of the composite transformer 3-4 and the output side of the amplifier is connected to the primary windings of a second composite transformer 17-18, which is in general similar to the transformer in the input circuit, the transformer 17 being designed for transmitting the telephone currents and the transformer 18 the telegraph currents. With the series arrangement of these transformers, here shown, balance is maintained as in the case of the input transformer by dividing the windings of one of the transformers in the middle and connecting the windings of the other between the halves. The attenuation equalizers are omitted in the output circuit but a condenser corresponding to condenser 15 in the input circuit is connected in parallel with each of the windings of the transformer 18 as at 19 and 20, to permit the free passage of telephone currents.

By this arrangement, the telephone impulses will be transmitted and amplified as usual, the various frequencies comprised within the telephone range being equalized in the circuit 7, and the alternating current component of the telegraph current, including all frequencies above a very low frequency, say two cycles, will be transmitted through the transformer 4, amplified at 16 and re-introduced into the transmission line 55 by the transformer 18; the attenuation of the various frequencies comprised within the telegraph range being equalized in the circuit 8 as in the case of the telephone currents. If it is desired to preserve the direct current component of the telegraph waves, this may be done by connecting high inductance shunts 21 around the transformer and amplifier as indicated on the drawing. When these are used large capacities 22 should be connected into the conductors

1-1, 2-2 between the connection of the high inductance shunts 21 and the transformer windings, to permit the passage to the transformer of all of the alternating current components, down to very low frequencies, while compelling the direct current component to pass on from the circuit 1 to the circuit 2 through the shunts 21. 70

In Fig. 2 the invention is illustrated as applied to a two-way two repeater circuit 75 the general characteristics of which are now too well-known to require detailed explanation. The amplifiers 23 and 24 transmit energy in opposite directions between the lines 24 and 25. The input circuit of each 80 repeater is connected to one of the lines through a composite transformer, 26 and 27 respectively, provided with attenuation equalizers for the telephone and telegraph currents and corresponding in all respects 85 with the apparatus shown in Fig. 1 between the line 1-1 and the amplifier 16. The output circuit of each repeater is connected to the other line through a special transformer 90 which combines the functions of the output transformer of Fig. 1 and those of the three winding transformer commonly employed in repeater circuits of this type. The primary windings of this transformer are indicated at 28, 29, 30 and 31 of which 28 and 29 together constitute the telephone winding and 30 and 31 the telegraph winding. The secondary windings 32, 33, 34 and 35 are located in the opposite sides of the line as usual, the windings 32 and 33 together constituting the telephone windings and the windings 34 and 35 the telegraph windings. The taps for the circuit leading to the input side of the amplifiers are taken off at the center of the composite windings, i. e. the 105 point where the halves of the telegraph transformer 30 and 31 join.

As in Fig. 1, the windings of the telegraph transformer are shunted by condensers 36 and 37 for permitting the free passage of 110 the telephone currents. The extremities of the two transformer windings 29 are connected to the artificial line N as usual in this type of repeater. If the inductive shunts 21', are used around the amplifiers 115 for carrying the direct current component of the telegraph wave, they will be connected directly to the respective circuits 24 and 25 as indicated in the drawing, and the condensers 22' will intervene between these 120 points of connection and the transformer windings 28.

In the modification shown in Fig. 3 the attenuation for both telephone and telegraph currents is effected in one circuit 38, 125 which is here shown as comprising elements corresponding generally to the separate equalizers for the telephone and telegraph currents shown in Fig. 1. Here also, the telephone transformer 39-40 is interposed 130

between the halves of the telegraph transformer 41—42. In general where a series arrangement is desired it is immaterial whether the telephone or the telegraph transformer be connected in the center.

If the telephone and telegraph channels are provided with separate attenuation equalizers, as in Figs. 1 and 2, there may be a band of frequencies between the telegraph 10 and telephone frequencies which is unequalized as indicated in Fig. 4 where frequency is plotted against attenuation. The attenuation of an ordinary loaded line is as indicated by the curve *a*. The attenuation 15 equalizer for the telephone currents will increase the attenuation of the lower frequencies, down say to 300, as indicated by the dotted line *b*. For lower frequencies the attenuation may if desired drop off 20 as indicated at *c* and the telegraph frequencies, say below 100, may then be equalized as indicated at *d*. This, of course, permits the telegraph frequencies to be equalized at an attenuation less than that of the 25 telephone frequencies. Where the two are equalized together, as in Fig. 3, or if separate equalizers are so designed, the attenuation for all frequencies will be the same as indicated by the dotted line *e* in Fig. 5.

30 It will be apparent that the arrangements above described permit of amplifying the telegraph currents, or the larger part thereof, without re-introducing, the high frequencies which in present practice must be 35 again removed by composite sets. Moreover, much greater amplification may be secured by the use of the thermionic amplifier and the arrangement permits of amplifying both 40 telephone and telegraph currents by a single device.

The use of the telephone and telegraph frequencies for illustrating the nature of the present invention is not to be taken as limiting its scope to such frequencies although 45 it is of peculiar value in connection with telegraph currents for reasons above indicated, and it will be understood that the invention is not limited to the details of circuit arrangement herein disclosed as it will 50 be obvious that various changes may be made without departing from the spirit of the invention.

What is claimed is:

1. In a signaling system the combination 55 of a main line for simultaneously transmitting telephone and telegraph currents, an amplifier adapted for simultaneously amplifying both currents, and means for equalizing the attenuation of the various frequencies comprised within the telephone range and within the telegraph range.
2. In a signaling system, the combination 60 of a main line for simultaneously transmitting telephone and telegraph currents, an amplifier adapted to simultaneously amplify

both currents, inductive connections between the line and the input and output circuits of the amplifier, and means for equalizing the attenuation of the frequencies within the telephone range and of the frequencies within 70 in the telegraph range.

3. In a signaling system, a combination of a main line for simultaneously transmitting telephone and telegraph currents, an amplifier adapted to simultaneously amplify both 75 currents, a composite transformer connecting the amplifier with the line on either side, and provided with separate windings for transmitting telephone and telegraph frequencies respectively, and attenuation equalizers for the telephone and telegraph frequencies connected respectively between the halves of the telephone and telegraph transformer windings.

4. A composite transformer for use on 85 composite telephone and telegraph lines comprising separate windings for the telephone and telegraph frequencies respectively, the windings for one set of frequencies being connected between the halves of 90 the windings for the other set of frequencies, means for by-passing the telephone frequencies around the windings designed for the telegraph frequencies, and attenuation equalizers for the telephone and telegraph frequencies respectively, connected between the halves of the transformer windings designed for the corresponding frequencies.

5. In a signaling system, the combination 100 of a main line for simultaneously transmitting telephone and telegraph currents, a two-way repeater in said main line comprising a separate amplifier for transmitting current in each direction, three-winding 105 transformers connecting the output circuits of the amplifiers with the line conductors leading in opposite direction, the secondaries of said transformers including like windings in the opposite sides of the 110 line, conductors leading from the central points of said secondary windings and a composite transformer connecting said conductors with the input circuits of said amplifiers, and having separate windings adapted 115 to transmit the telephone and telegraph frequencies respectively.

6. In a signaling system, the combination of a main line for simultaneously transmitting telephone and telegraph currents, a two-way repeater in said main line comprising 120 a separate amplifier for transmitting current in each direction, three-winding transformers connecting the output circuits of the amplifiers with the line conductors leading in opposite directions, the secondaries of said transformers including like windings in the opposite sides of the lines, conductors leading from the central points of 125 said secondary windings, a composite trans- 130

former connecting said conductors with the input circuits of said amplifiers, and having the separate windings adapted to transmit the telephone and telegraph frequencies respectively, the three-winding transformers comprising separate windings for transmitting the telephone and telegraph frequencies respectively.

7. In a signaling system, the combination 10 of a main line for simultaneously transmitting telephone and telegraph currents, an amplifier adapted for simultaneously amplifying both currents, inductive connections between the line and the input and output 15 circuits of the amplifier comprising sections for transmitting the telephone and telegraph currents respectively, and means for bypassing the direct current component of the telegraph current around the amplifier and 20 its inductive connections.

8. In a signaling system the combination of a main line for simultaneously transmitting telephone and telegraph currents, an amplifier adapted to simultaneously amplify both currents, inductive connections between the line and the input and output circuits of the amplifier, comprising sections for transmitting the telephone and telegraph frequencies respectively, high inductance shunts directly connecting the sections of the main line on opposite sides of the amplifier and its inductive connections, and condensers located in the main line conductors between their connection with the high inductive shunts and said inductive 35 connections.

In testimony whereof, I have signed my name to this specification this seventeenth day of December, 1918.

LLOYD ESPENSCHIED.
